UNITED STATES PATENT OFFICE

2,531,617

ARRANGEMENT IN COMPRESSED AIR
CIRCUIT BREAKERS

Haakon Forwald, Valhalla, Ludvika, Sweden, assignor to Alimanna Svenska Elektriska Aktiebolaget, Västeras, Sweden, a Swedish corporation

Application January 17, 1948, Serial No. 2,914
In Sweden March 24, 1943

Section 1, Public Law 690, August 8, 1946
Patent expires March 24, 1963

2 Claims. (Cl. 200—148)

1

The present invention has for its object to provide a compressed air circuit breaker with a plurality of series connected contact pairs in which the blow-out opening of a contact pair is closed by a valve when the movable contact of a consecutive contact pair has terminated its opening stroke. The main feature of the invention is that the said blow-out opening valves as well as the movable contacts are operated by compressed air delivered from an operating valve separate from the valve controlling the delivery of extinguishing air to the breaker. Another feature of the invention is that the operating air for the said blow-out opening valves is controlled by the motion of the movable contacts, so that the said valves are closed after the movable contacts have terminated their motion.

It has heretofore been proposed to operate the movable contacts as well as the said valves by the arc extinguishing air. This arrangement, however, has the disadvantage that the contacts may be opened before the extinguishing air in the breakers has reached a sufficient pressure, and as the motion of said valves is dependent upon the motion of the movable contacts, said valves may become closed before the arcs have been extinguished.

In accordance with the present invention, this disadvantage is avoided, since the movable contacts and the valves are operated by air from a separate operating valve.

The invention is illustrated on the accompanying drawing, where 1 designates the bottom plate of the circuit breaker, 2 a compressed air container, 3 an extinguishing air valve and 4 an operating air valve. The circuit breaker rests on an insulating cylinder 5, which is arranged on the bottom plate 1 of the circuit breaker, and 6 is an insulator carrying the stationary contact of the disconnecting switch. 7 is the contact arm of the disconnecting switch, which is operated by the insulating shaft 8. On the insulating cylinder 5 a series of insulating cylinders 9 are arranged, which cylinders 9 are connected with the insulator 5 and with each other by means of connecting pieces 10 of metal. The stationary contacts 11 are formed as sleeve contacts, and the movable contacts are designated 12. These contacts 12 are, by means of rods 13, connected with operating pistons 14, which move in operating cylinders 15. The blow-out openings for the contact pairs are designated by 16 and are formed in the stationary contacts. The escape of air from the contact pairs is controlled by valve members 17, which

2

are operated by valve operating pistons 18 movable in valve operating cylinders 19.

In operation, at the opening of the circuit breaker, the extinguishing valve 3 and the operating valve 4 are opened, the valve 3 being opened a little before the valve 4, so that the whole circuit breaker becomes filled with compressed air before the contacts separate. When the valve 4 is then opened, air flows up through the operating pipe line 20 to the upper sides of the contact operating pistons 14, and the movable contacts 12 then moving downwards. When the pistons 14 have reached their lower position, a passage 21 between the upper cylinder 15 and the lower cylinder 19 is opened, so that the operating air can also reach the upper side of the lower piston 18. When this piston 18 has commenced its motion, a direct passage 21a from the pipe line 20 to the upper part of the lower cylinder 19 is opened. 20 When closing the breaker, the operating valve 4 is closed, and the contact pistons 14 and valve pistons 18 move back to their original positions, being actuated by springs.

For the operating cylinder of the lowermost 25 breaking gaps, an operating passage such as 21 is of course not necessary, and for the closing arrangement of the uppermost blow-out opening, a damping of the motion of the piston 18 must be taken care of, so that the blow-out opening of this breaking gap is not closed before the movable contact has reached its end position.

I claim as my invention:

1. A compressed air circuit breaker with series connected contact pairs, comprising movable contacts and stationary contacts, a blow-out opening for each contact pair, an extinguishing air valve for the delivery of extinguishing air to said contact pairs, contact operating cylinders, operating pistons movable in said operating cylinders for operating said movable contacts, a separate pipe line directly connecting said operating cylinders with a compressed air container, an operating valve in said pipe line, a valve member for each contact pair for closing the blow-out opening from a consecutive contact pair, an operating piston for each of said valve members, a valve operating cylinder for each of said valve operating pistons, and means giving the contact operating air access to each of said valve operating cylinders, when said contact operating piston in a preceding contact pair has terminated its opening stroke.

2. A compressed air circuit breaker with series connected contact pairs, comprising movable contacts and stationary contacts, a blow-out opening for each contact pair, an extinguishing air valve

for the delivery of extinguishing air to said contact pairs, operating cylinders, operating pistons movable in said operating cylinders for operating said movable contacts, a separate operating air pipe line connecting said operating cylinders directly with a compressed air container, an operating valve in said pipe line, a valve member for each contact pair for closing a blow-out opening from a consecutive contact pair, an operating piston for each of said valve members, a cylinder for each of said valve operating pistons, a passage from the said contact operating cylinder of one contact pair to the valve operating cylinder of a consecutive contact pair, giving the operating air access to the upper side of said valve

15

operating piston when said contact operating piston in a preceding contact pair has terminated its opening stroke, and a passage from the said operating air pipe line to the valve operating cylinder opened by the valve operating piston at the commencement of its motion.

HAAKON FORWALD.
